CABINET CONSTRUCTION

Joseph W. Jensen, Chicago, Ill., assignor to Electric Household Utilities Corporation, Chicago, Ill., a corporation of Illinois

Application August 5, 1937, Serial No. 157,473

5 Claims. (Cl. 45—68.1)

The present invention relates to cabinet constructions of the type including a table-like support on which an instrument or a like unit is mounted, and more particularly to means associated with the support for enclosing the instrument or unit.

Closure means, or covers of the general character to which this invention relates, have heretofore generally been formed as inverted box-like structures, of minimum height, and having a flat top, adapted to serve as an auxiliary supporting surface when the apparatus is of the type used in the home. In practically all instances such closures or covers have heretofore been formed as a unitary element, and in most instances its dimensions are of such size as to render it difficult to handle, particularly in cases where such types of closures are bodily removed from the table-like support. In some forms of apparatus 20 of this general class, the closure means is associated with the support in a manner to permit pivotal movement thereof; permitting swinging to and from operative position relatively to the table-like support. In many of such constructions, however, the closure means, when removed to expose the instrument or like unit, is compelled to occupy a space immediately rearwardly of the support, or at one end thereof. Obviously, when such apparatus are normally 25 positioned in close proximity to a wall, it is first necessary to pull them away from the wall a sufficient distance to provide adequate clearance for accommodating the closure means. Moreover, the provision of suitable means connecting the closure means and the support for controlling the movement of closure means from one 30 position to another, materially adds to the cost of fabrication.

One of the objects of the present invention 40 resides in the provision of a novel and improved form of a closure means, of the character indicated, which obviates the foregoing objections, and which may be quickly and conveniently handled for exposing or enclosing the instrument or like unit on the table support.

Another object of this invention is to provide an improved closure means of the character indicated, wherein said closure means is composed of a plurality of independently movable bodies, and 45 wherein at least one of said bodies is constructed so that when removed from normal closing position, it may be disposed in association with the table-like support in a manner to constitute a shelf or extension thereof.

50 A further object resides in the provision of a

closure of the character indicated, comprising a plurality of independently movable bodies characterized by the provision of interengaging features between one or more of said bodies, and the table-like support, for positioning said bodies for enclosing the instrument or like unit, or for supporting one or more of said bodies in association with the table-like support in a manner to constitute a shelf or extension thereof.

5 Other objects and advantages of this invention 10 will be apparent from the following description taken in connection with the accompanying drawings, in which—

Fig. 1 is a perspective view of a table-like support and closure means constituting the present 15 invention.

Fig. 2 is a perspective view similar to Fig. 1 showing the closure means associated with the table-like support in a manner to constitute shelves or extensions thereof.

20 Fig. 3 is a perspective view of one of the independently movable bodies of the closure means, shown positioned, on a floor, remote from the table-like support.

Fig. 4 is a fragmentary vertical sectional view 25 taken substantially as indicated at line 4—4 on Fig. 1.

Fig. 5 is a fragmentary horizontal sectional view taken as indicated on line 5—5 on Fig. 2.

Fig. 6 is a fragmentary transverse sectional 30 view through the plane of abutment of the closure bodies, taken as indicated at line 6—6 on Fig. 1.

Fig. 7 is an end view looking into the interior of one of the bodies of the closure means.

Fig. 8 is a bottom view looking into the interior of one of said bodies of the closure means.

For purposes of illustration, I have herein shown the present invention in connection with a table-like structure having mounted thereon an ironing machine of the character usually employed in the home. It will be apparent, however, that the present invention is capable of adaption to various other apparatus including an instrument or a like unit mounted on a table- 45 like support.

In the drawings the table-like support is shown as of generally rectangular shape, formed of sheet metal and including a top 10 and end supports, herein shown, formed as panels 11, the vertical 50 edges of which are bent angularly for purpose of reinforcement, and serving the function of leg members. The entire marginal edge of said top is formed with a depending reinforcing flange or skirt 10a, overlying and secured to said end panels, 55

as seen in the drawings. Secured adjacent to the lower portion of each end panel is a horizontally disposed reinforcing member 12, the rearward ends of which are connected to and reinforced by a tie member 13. Secured in the corners, formed by the angularly bent portions of the respective end panels, are brackets 14 constituting sockets for conventional caster wheels indicated at 15. Mounted on the support top 10, as seen in the drawings, is a conventional ironing machine mechanism, designated generally at A, the dimensions of which are such as to lie within the marginal edges of the top 10.

The means for enclosing the ironer unit, as above mentioned, preferably is formed to present a flat top to constitute an auxiliary supporting surface, and in the structure embodying this invention, the closure means includes two cooperating inverted box-like bodies 17 and 18, formed of sheet metal, which are disposed in abutting relation, as seen in Figs. 1 and 6. For convenience and economy in manufacture, these box-like bodies are substantially identical in construction with the exception that of one of the bodies as indicated at 17 is provided with an encompassing band 19, rigidly united thereto, surrounding and extending beyond its open end, which is disclosed in abutting relation to the corresponding end of the body 18. The band 19 may be formed of ornamental contour, preferably plated, to enhance the appearance. The extension of the band 19 beyond the marginal edge constituting the open end of closure body 17, permits telescoping of the corresponding end of the adjacent body 18 thereinto, as seen in Fig. 6, and also serves to preclude lateral displacement of one body relatively to the other, in the general direction of the plane of abutment of said bodies.

In order that the open ends of these closure bodies may be sufficiently strong so that the entire top of the closure may effectively serve to support objects, said abutting open ends of the bodies are each reinforced by folding marginal portions inwardly to form flange portions, 20, across the top and the sides of said bodies; said flanges being disposed in spaced apart relation to the panels of the body to form pockets. Rigidly secured in each of said pockets is a leg of a reinforcing member 21 of angular cross-section, the other leg of which extends at substantially right angles to the top and sides of the body. The portions of said last mentioned legs, at their juncture between the top and sides of the body, are increased in width to serve as gusset plates. The lower marginal portions of the sides and ends of said bodies are also folded in a similar manner to form flanges 22 which are engaged and reinforced by a member 23, similar to member 21.

The lower marginal edge of each of said bodies is provided with a strip of padding or resilient material, as indicated at 25, such as of rubber, which, as herein shown in the drawings, is formed with a U-shaped slot for frictionally securing it to said lower edge of the body. Similar strips 26, of resilient material, are secured to the inwardly extending legs of the reinforcing member 23, as seen in Fig. 8. These resilient strips 25 and 26 are adapted to seat upon and embrace the marginal edges of the top 10 of the table-like structure, as seen in Fig. 4, and serve to prevent possible damage to the finish of said table top, which may be enamel, paint or any other suitable finish. Said resilient strips further serve to eliminate noise incident to the placing of the closure bodies in position on the table

top. Particularly in connection with ironing machines, it is usually desirable to have auxiliary supporting surfaces in addition to the table top for supporting fabric to be ironed or fabrics that have been ironed, or for supporting devices used in connection with the ironing operation, such as a sponge, pan of water, or a spraying device. By virtue of the present invention, the closure means is formed so that it may be handled conveniently in sections, and each section or body may be placed upon the floor, if desired, adjacent the ironing machine, as seen in Fig. 3, to serve the purpose of convenient auxiliary support for articles.

If desired, either or both of said bodies may be utilized in direct association with the table-like structure to constitute end shelves or extensions of the table top 10. For this purpose the respective bodies 17 and 18, and the table top 10 are provided with interengaging features, comprising a projection 28 adjacent the lower edge of the end panel of each of the closure bodies, as seen in Figs. 4 and 5. Said projection is formed with a reduced shank 29, the end of which protrudes through the respective reinforcing flange 22 and the leg of the reinforcing member 23, and is riveted thereto, as indicated at 30. The projections 28 are adapted to enter aligned apertures 10^b, formed in the top 10 of the table-like structure, adjacent the respective ends thereof. For convenience, the projections 28 are each formed with a depending off-set shoulder 31, which as seen in Fig. 4 is adapted to normally extend below the lower edge of the aperture 10^b of the table top to preclude removal or separation of the closure bodies by a direct end-wise pull. The bodies 17 and 18 may be separately removed by slight rearward upward movement at the outer ends thereof, so as to raise the shoulder of the projection above the edge of the aperture, and then by direct rearward movement, the body may be freely removed from the top of the table 10. When it is desired to employ either or both of these bodies as shelves, or extensions, at the ends of the table top 10, the bodies are merely inverted to the position seen in Fig. 2, and the projections 28 are inserted into the apertures 10^b so that the end panel of each body is supported and disposed in a horizontal plane substantially parallel to the top 10, and constituting an extension thereof, as seen in Figs. 2 and 5. In this position of the bodies, the resilient padding or strips 25 embrace the marginal end portions of the top 10, and the vertical front and back flanges of the end panels 11, and thus said resilient strips 25 serve to protect the finish, such as enamelled surfaces, of said end panel against possible injury or defacement.

It will be apparent that due to the small size of the respective bodies or sections, the matter of lifting them for proper positioning, either for enclosing the unit, or for utilization as extension shelves, or as separate supporting devices when placed on the floor, requires relatively little effort. This construction also has the decided advantage in that it does not necessitate any appreciable movement of the apparatus away from a wall or other objects in the removal of the closure means for exposing the instrument or like unit for use. In relatively small quarters this is a decided advantage.

Although I have herein shown and described a particular embodiment of my invention, manifestly it is capable of modification and rearrangement without departing from the spirit and scope

thereof. I do not, therefore, wish to be understood as limiting this invention to the precise embodiment herein shown and described, except as it may be so limited in the appended claims.

5 I claim:

1. The combination with a table-like structure and an instrument or like unit mounted thereon; of bodily removable means adapted to be seated on said table-like structure for enclosing said instrument, and interengaging features on said table-like structure and said closure means for maintaining the latter in proper position on the former, said interengaging features being formed for detachably supporting the closure means adjacent one edge of the table-like structure in a position to constitute a shelf or extension.

2. The combination with a table-like structure and an instrument or like unit mounted thereon; of bodily removable means adapted to be seated on the table-like structure for enclosing the instrument, said means being of generally rectangular box-like form, composed of a plurality of independently movable bodies adapted to be disposed in end-to-end abutting relation, and interengaging features on said table-like support and one of said bodies adapted to maintain the latter in position on the former, said interengaging features being formed for supporting said one body adjacent one edge of the support to constitute a shelf or extension.

3. The combination with a table-like structure and an instrument or like unit mounted thereon; of bodily removable means adapted to be seated on the table-like structure for enclosing the instrument, said means being of generally rectangular box-like form, composed of a plurality of independently movable bodies adapted to be disposed in end-to-end abutting relation, and interengaging features on said table-like support and one of said bodies adapted to maintain the latter in position on the former, said interengaging

features including a projection extending inwardly from the lower portion of the outer end of said body, when in enclosing position, engageable in an aperture formed in the adjacent marginal edge of the table-like support, for supporting said body adjacent the support to constitute a shelf or extension.

4. The combination with a table-like structure and an instrument or like unit mounted thereon; of bodily removable means adapted to be seated on the table-like structure for enclosing the instrument, said means being of generally rectangular box-like form, composed of a plurality of independently movable bodies adapted to be disposed in end-to-end abutting relation, resilient pad means secured to the lower edge of one of said bodies when it is in enclosing position for seating upon the table-like support, said body being formed for detachable securement in overlapped relation to and adjacent one edge of the support to constitute a shelf or extension, with the resilient pad means seated against the support.

5. The combination with a table-like structure and an instrument or like unit mounted thereon; of bodily removable means adapted to be seated on the table-like structure for enclosing the instrument, said means being of generally rectangular box-like form, composed of a plurality of independently movable bodies adapted to be disposed in end-to-end abutting relation, and interengaging features on said table-like support and one of said bodies adapted to maintain the latter in position on the former, said interengaging features being formed for supporting said one body adjacent one edge of the support to constitute a shelf or extension, said features including a projection on the body, adjacent its lower edge, and an aligned aperture at a corresponding edge of the support.

JOSEPH W. JENSEN.
